Primary Examiner — Joseph Kukella*Assistant Examiner* — Laron M. Amerson(74) *Attorney, Agent, or Firm* — Quarles & Brady LLP(57) **CLAIM**

The ornamental design for a vehicle roof with foldable lidar, as shown and described.

DESCRIPTION

FIG. 1 is a front elevation view of a vehicle roof with foldable lidar embodying our new design with the foldable lidar in a closed configuration;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a top, rear, right side perspective view thereof;

FIG. 8 is a front elevation view of the vehicle roof with foldable lidar with the foldable lidar in an opened configuration;

FIG. 9 is a rear elevation view thereof;

FIG. 10 is a left elevation view thereof;

FIG. 11 is a right elevation view thereof;

FIG. 12 is a top plan view thereof;

FIG. 13 is a bottom plan view thereof; and,

FIG. 14 is a top, rear, right side perspective view thereof.
